UNITED STATES PATENT OFFICE.

GEORGE ALFRED BRYAN, OF PERU, INDIANA, ASSIGNOR TO BRYAN HARVESTER COMPANY, INC., A CORPORATION OF NEW MEXICO.

TRACTOR.

Application filed April 7, 1922. Serial No. 550,328.

To all whom it may concern:

Be it known that I, GEORGE A. BRYAN, a citizen of the United States, residing at Peru, in the county of Miami and State of Indiana, have invented certain new and useful Improvements in Tractors, of which the following is a full, clear, and exact description.

My invention relates to tractors, and has especial reference to means for utilizing the tractor as a stationary power device. It is customary for this purpose to equip the tractor with a belt pulley which is coupled to the machinery to be driven by a belt. Frequently the pulley is on the end of a special transverse shaft provided for the purpose, which is either operatively connected to the transmission gearing leading to the differential on the rear axle or has an independent drive connection with the engine. In some cases where the shaft is coupled to the transmission gearing it is necessary to raise the rear wheels from the ground when using the tractor as a stationary power device, although it has been proposed to provide means for alternately coupling the first gear of the transmission train with the pulley shaft drive and with the rest of the transmission train.

In accordance with my invention, I simplify this construction by employing a counter shaft adapted to receive and hold a pulley on one projecting end and properly located to drive the fan through gearing or other suitable connection, and this counter shaft has permanent drive connection with the transmission gearing in advance of disabling means provided to interrupt the connection with the differential.

My invention also comprehends other features of construction and details and arrangement of parts as will hereinafter more fully appear. I shall now describe the illustrated embodiment of my invention and shall thereafter point out my invention in claims.

Fig. 1 is a plan of a tractor embodying my invention;

Fig. 2 is a side elevation of the same;

Fig. 3 is a front end elevation of the frame and pulley shaft and housing support therefor;

Fig. 4 is an enlarged sectional plan of the parts at the pulley end of the shaft.

The illustrated tractor is steam propelled following generally the design of the vehicle illustrated in my co-pending application, Serial No. 535,167, filed February 9, 1922. Mounted on the front end of the chassis frame is a suitable steam generator 1 in front of which is a condenser 2. In the rear of the steam generator is the steam engine 3 and on the rear axle suitably supported on the chassis frame is the transmission gear case 4. The engine shaft 5 extends transversely of the frame and is supported in the front end of the transmission gear case 4. A spur gear wheel 6 on the engine shaft 5 meshes with the first gear 7 of the transmission train, which gear 7 is fixed on the stub shaft 8 journalled in bearings in the transmission gear case. On the stub shaft 8 is splined a pinion 9 which is shiftable into and out of mesh with the spur gear wheel 10 on shaft 11, also journalled in bearings 75 in the case 4 in rear of the shaft 8. A pinion 12 on shaft 11 meshes with gear wheel 13 on the rear axle which is connected to any suitable type of differential. It is, therefore, apparent that the transmission train connecting the engine shaft with the rear axle may be disabled by shifting the gear 9.

Secured to the left side of the transmission gear case 4 is a gear box 14. The stub shaft 8 extends into this gear box 14 and has on its end a bevel gear 15 meshing with a bevel gear 15' on a longitudinally extending stub shaft 16. This stub shaft 16 is connected to and drives a universally jointed, longitudinally extending shaft 17, the front end of which is coupled to a stub shaft 18 in a gear box 19 at the front end of the tractor.

The transverse fan drive and pulley shaft 20 which bears at its one end in the gear box 19 is supported in the space between the boiler 1 and the condenser 2 in the manner illustrated in Figures 2 and 3. Connecting the front ends of the side frame members 21 and 22 is a frame front bracket 23 which is pinned at its central point to the front axle 24, and has at its ends two forwardly projecting arms 25 and 26 on which the condenser 2 is supported. Secured to the top

of this frame front bracket 23 is a pulley shaft housing support 27 on the one end of which is supported the gear box 19 and on the opposite end of which is supported the bearing 28 for the opposite end of the pulley shaft. Midway between the gear box 19 and the bearing 28 is supported a fan drive gear box 29.

A bevel gear 30 on the stub shaft 18 meshes with a bevel gear 31 on the end of the pulley shaft in the gear box 19. Spiral gears in the fan drive gear box 29 serve to drive the stub shaft 32 on the front end of which is secured a fan 33.

15 The end of the shaft 20 which projects beyond the bearing 28 is adapted to receive and rotate the belt pulley 34. The end of the shaft has two reductions in diameter, the first reduction forming a shoulder 35, 20 and the extreme end of the shaft is screw threaded. Surrounding the second reduced portion of the shaft is a sleeve 36, the outer end of which is screw threaded and which has a circumferential flange 37. A nut 38 on 25 the threaded end of the shaft 20 clamps the sleeve 36 and a bushing 36^a on the first reduced portion tightly against the shoulder 35, thus locking the sleeve and shaft together 30 against relative rotation, although other well-known means of non-rotatively securing the sleeve on the shaft may be employed.

The pulley 34 has a central flat hub portion which fits over the sleeve 36 and bears against the flange 37. Suitable means for 35 locking the two together against relative rotation are employed, in this case studs 38^a being used for the purpose. The studs are carried by one of the members, preferably the flange, and the other member, in this 40 case the hub, is provided with properly spaced holes to receive the studs. A nut 39 on the screw threaded end of the sleeve 36 locks the pulley in place.

45 By these means the pulley may easily be put on or removed. If desired, a suitable cap may cover the exposed end of the shaft when the pulley is removed. It is obvious that various modifications may be made in the construction shown in the drawings and 50 above particularly described within the principle and scope of the invention.

I claim:

1. In a tractor having a rear axle, an engine the shaft of which extends transversely 55 of the tractor, an interruptable drive connection between the engine shaft and rear axle, a power shaft extending longitudinally of the tractor and connected with the transverse engine shaft to be driven thereby, a 60 power delivery shaft extending transversely of the tractor and having a driving connection with the longitudinal power shaft, and a fan connected to be driven by one of the last two mentioned shafts.
- 65 2. In a tractor having a rear axle, an en-

gine the shaft of which is disposed close to and parallel with the rear axle, an interruptable drive connection between the engine shaft and rear axle, a power shaft extending longitudinally of the tractor and connected with the transverse engine shaft to be driven thereby independently of the said interruptable connection, a power delivery shaft extending transversely of the tractor and having a driving connection with the longitudinal power shaft, a fan connected to be driven by one of the last two mentioned shafts, and means on the end of the power delivery shaft for receiving and holding a belt pulley.

3. In a tractor, in combination with an engine shaft, a fan and the rear axle, a transverse shaft operatively connected to the fan, means on the end of the transverse shaft for receiving and holding a belt pulley, a longitudinal shaft having a drive connection at its front end with the transverse shaft, transmission gearing connecting the engine shaft to the rear axle and including disabling means, and means operatively connecting the rear end of the longitudinal shaft to the transmission gearing in advance of the disabling means.

4. In a tractor, in combination with the rear axle and the frame, a steam engine, boiler, condenser and transmission gear case supported on the frame, a transverse combined fan drive and pulley shaft mounted between the boiler and condenser, a longitudinal shaft having a drive connection at its front end with the transverse shaft, an engine shaft, means permanently operatively connecting the engine shaft to the rear end of the longitudinal shaft, transmission gearing in the gear case connected to the rear axle, and shiftable means for connecting and disconnecting the engine shaft and transmission gearing.

5. In a tractor, in combination with the rear axle and the frame, a steam engine, boiler, condenser, and transmission gear case supported on the frame, a transverse combined fan drive and pulley shaft mounted between the boiler and condenser, a longitudinal shaft having a drive connection at its front end with the transverse shaft, a transverse engine shaft supported in the gear case, transmission gearing in the gear case connecting the engine shaft to the rear axle and including disabling means, and means operatively connecting the rear end of the longitudinal shaft to the transmission gearing in advance of the disabling means.

6. In a tractor, in combination with the rear axle and the frame, a steam engine, boiler, condenser, and transmission gear case supported on the frame, a transverse combined fan drive and pulley shaft mounted between the boiler and condenser, a longi-

longitudinal shaft having a drive connection at its front end with the transverse shaft, a transverse engine shaft having a gear wheel thereon, a stub shaft mounted in the gear case permanently geared to the rear end of the longitudinal shaft and having a fixed gear wheel thereon meshing with the gear wheel on the engine shaft, transmission gearing in the gear case connected to the rear axle, and a shiftable gear on the stub shaft movable into and out of operative connection with the transmission gearing.

In witness whereof, I hereunto subscribe my signature.

GEORGE ALFRED BRYAN.
